TABLET ARM CHAIR

Earl E. Alverson, Birmingham, Ala., assignor to South-eastern Metals Company, North Birmingham, Ala.

Filed Feb. 27, 1958, Ser. No. 49,822

Term of patent 14 years

(Cl. D33—11)

FIG. 1.

FIG. 2.

FIG. 3.

FIG. 1 is a front perspective view of a tablet arm chair showing my new design;

FIG. 2 is a side elevation thereof, and

FIG. 3 is a bottom view.

The dominant features of my design reside in those portions shown in full lines on the drawing.

I claim:

The ornamental design for a tablet arm chair, as shown and described.
